DESIGN FOR AN ASHTRAY

William E. Mackelfresh, Jr., Chicago, Ill., assignor to Owens-Illinois Glass Company, Toledo, Ohio, a corporation of Ohio

Application October 1, 1936, Serial No. 65,111

Term of patent 3½ years

To all whom it may concern:

Be it known that I, William E. Mackelfresh, Jr., a citizen of the United States, and residing at Chicago, in the county of Cook and State of Illinois, have invented a new, original, and ornamental Design for an Ashtray, of which the following is a specification, reference being had to the accompanying drawing, forming a part thereof.

In the drawing:

Fig. 1 is a plan view of an ashtray showing my new design;

Fig. 2 is a side elevational view thereof; and
Fig. 3 is an end elevational view thereof.

I claim:

The ornamental design for an ashtray substantially as shown.

WILLIAM E. MACKELFRESH, JR.
